LAMP HOLDER

Leonard Atkin, Springfield, N.J., assignor to Stone Manufacturing Co., a corporation of New Jersey

Application December 12, 1958, Serial No. 53,741

Term of patent 14 years

(Cl. D48—20)

FIG. 1

FIG. 2

FIG. 4

I claim:

The ornamental design for a lamp holder, substantially as shown.
